US0D1021720S

(12) **United States Design Patent** (10) **Patent No.:** **US D1,021,720 S**
(45) **Date of Patent:** **** Apr. 9, 2024**

(54) **VEHICLE FENDER**

(71) Applicant: **Ford Global Technologies, LLC**,
Dearborn, MI (US)

(72) Inventors: **Joel Piaskowski**, Birmingham, MI (US); **Doyle Letson**, Novi, MI (US); **Christopher Walter**, Traverse City, MI (US); **Omead Dorandish**, Superior Township, MI (US); **Christopher Stevens**, Detroit, MI (US)

(73) Assignee: **Ford Global Technologies, LLC**,
Dearborn, MI (US)

(**) Term: **15 Years**

(21) Appl. No.: **29/844,253**

(22) Filed: **Jun. 28, 2022**

(51) **LOC (14) Cl.** **12-16**

(52) **U.S. Cl.**

USPC **D12/184**

(57) **CLAIM**

The ornamental design for a vehicle fender, as shown and described.

DESCRIPTION

FIG. 1 is a front elevational view of a vehicle fender, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a top, front and right side perspective view thereof. The ghosted or low contrasted portions of the vehicle fender illustrate portions that form no part of the claimed design.

1 Claim, 7 Drawing Sheets
